UNITED STATES PATENT OFFICE.

FREDERICK A. LANE, OF WATERVILLE, MAINE.

FLY-TRAP.

SPECIFICATION forming part of Letters Patent No. 594,698, dated November 30, 1897.

Application filed August 3, 1897. Serial No. 646,933. (No model.)

To all whom it may concern:

Be it known that I, FREDERICK A. LANE, a citizen of the United States, residing at Waterville, in the county of Kennebec and State 5 of Maine, have invented certain new and useful Improvements in Fly-Traps; and I do hereby declare the following to be a full, clear, and exact description of the invention, such as will enable others skilled in the art to which 10 it appertains to make and use the same.

The object of this invention is to provide an automatic intermittently-acting mechanical fly-trap which will be capable of continuing in operation for a considerable length 15 of time without requiring the care of any attendant. To this end I employ a pair of crushing boards or plates, automatic means for bringing them together, clockwork mechanism and connections for drawing one of 20 said boards or plates from the other, and a tripping device which periodically sets this board free to be sprung into contact with the other board again by the automatic means aforesaid.

25 In the accompanying drawing the figure represents a perspective view of the fly-trap in its open position, its closed position being indicated by dotted lines.

A designates the platform or bed of the 30 fly-trap, having at one end standards B B' and at the other standards C C'. To this latter pair a crushing plate or board D is fixed in an upright position. A corresponding movable plate or board E is mounted on 35 guides on the said bed or platform and drawn at intervals with a sudden snap against the former plate or board by two strong springs F, catching and crushing the flies that have alighted or are about to alight on the afore- 40 said stationary crushing plate or board D. They then fall, being dislodged by a slight resiliency of jaws D E, into a dead-fly receptacle G below the same. Molasses or other fly-tempting material is smeared over the 45 board or jaw D or otherwise used to serve as a bait.

To provide for regularly opening and permitting the periodical sudden closure of the pair of spring-jaws D E thus formed a series 50 of wires or equivalent connections H extend from convenient points of the flat movable jaw E to a cord or chain I, which winds on

a drum or pulley J, loosely mounted on a shaft K, that carries also a fast pulley or drum L and a fast pinion M. The said pinion meshes with a main wheel N, loose on a winding-shaft O, said wheel being driven by a clock-spring P, which is attached to the said shaft at one end and to this main wheel at the other. This winding-shaft is provided 55 with a crank-handle Q, whereby the said spring is wound once in twelve or fourteen hours, being calculated to run for about that period. A train of wheels and pinions which are individually lettered, respectively, R S 60 T U V and mounted on short shafts t, u, and v, makes connection between the wheel N and the latter shaft, whereon is mounted an escapement-wheel W, turning therewith. A pivoted weighted double pawl X of the anchor 65 kind engages this escapement-wheel for regulating the speed of wheel N. This pawl is provided with a pendulum, and the extent of its vibration is governed by a set-screw n.

The main wheel N drives the fast pulley 70 or drum L by means of pinion M and its shaft K. The said pulley carries a pivoted angular latch Z, which is provided with a short lateral arm Z', arranged to engage an inclined pin Z² on the loose pulley or drum J, so that 75 the two pulleys will turn together. This latch has also a long forward arm or arms Z³, arranged to be struck and depressed by one or more of the connections H when these are drawn to that point by the winding of chain 80 or cord I. The effect of such contact is to depress the arm Z³ and raise the arm Z' until the latter is moved out of contact with the pin Z², thus freeing the loose pulley J and the movable plate, board, or flat jaw E. The 85 springs F, being then at liberty to act, suddenly snaps the jaw E against the jaw D, as aforesaid, while a replacing-spring y on pulley L restores the latch Z to its first position. At the next rotation of the said pulley the 90 arm Z' is again in contact with the pin Z² and the two pulleys or drums turn together, as before.

By this construction of my fly-trap I am enabled to get automatic action, alternately 100 opening and closing, extending through a number of hours, with no need of personal supervision. When the mainspring runs down, the dead flies are removed, the crank

is turned for winding again, and the trap is placed in readiness for another long period of automatic service.

Any other mechanical motor or power suitable to such work might be substituted for the particular construction of clock-spring and gearing which I have shown without departing from the scope of the broader features of my invention.

Having thus described my invention, what I claim as new, and desire to secure by Letters Patent, is—

1. An automatically-closing fly-trap, in combination with means for automatically opening the same and automatic tripping devices, whereby it is periodically freed from the means for opening it, in order to permit such automatic closure substantially as set forth.
2. In a fly-trap a fixed jaw and a corresponding jaw movable toward and from the same, a mechanical power and connections operating to draw the latter jaw away from the former and tripping devices which periodically free the said movable jaw from the said power to permit closure substantially as set forth.
3. A rotary shaft and two pulleys, one fast and the other loose thereon, in combination with a mechanical power automatically driving the said shaft, a pair of spring-closed insect-killing jaws, a connection from one of said jaws to the said loose pulley on which it is wound, and a latch on the fast pulley engaging a pin on the loose pulley while having an arm arranged for contact with a part of such connection in order that said latch may

be tripped from said pin, freeing the loose pulley and movable jaw at certain intervals substantially as set forth.

4. In combination with a pair of spring-closed jaws for killing flies and other insects a cord and pulley and attachments for opening the said jaws, a shaft on which the said pulley is loosely mounted, a pulley fast on said shaft, separable connections between said pulleys arranged to be freed by attachments of the said cord at regular intervals, a clock-spring and gearing whereby the said shaft is driven and an escapement controlling the action of the said spring substantially as set forth.

5. In combination with a mechanical power and a shaft driven thereby, a fast pulley and a loose pulley on the said shaft, a pin on the loose pulley, a latch having an arm in contact with said pin and another forwardly-extending arm, a cord winding on the said loose pulley and provided with means for acting on the said forward arm to lift said latch out of engagement with said pin, a spring on the said fast pulley for restoring the said latch to its normal position and a pair of fly-crushing jaws, one of which is attached to the cord and withdrawn by the winding of the said cord until the said latch is tripped from the said pin as hereinbefore described.

In testimony whereof I affix my signature in presence of two witnesses.

FREDERICK A. LANE.
